REFRIGERATION SYSTEM

Alwin B. Newton, Minneapolis, Minn., assignor to
 Minneapolis-Honeywell Regulator Company,
 Minneapolis, Minn., a corporation of Delaware

Application March 31, 1938, Serial No. 199,216

19 Claims. (Cl. 62—4)

This invention relates to a refrigerating system and more particularly to a refrigerating system of the mechanical type.

One of the objects of this invention is the provision of a novel arrangement for more efficiently operating a refrigeration system.

More specifically it is an object of this invention to provide a refrigeration system of the mechanical type wherein the condenser is positioned in a location subject to wide temperature variations and wherein means are provided for circulating refrigerant from the condenser to the evaporator without the use of the compressor during such times as the temperature of the air surrounding the condenser is lower than the temperature to be maintained in the space being cooled by the evaporator.

Another object of this invention is the provision of a refrigeration system having a pair of condensers connected together in parallel, one of the condensers being positioned in a location subject to wide temperature variations, whereby the condenser which is surrounded by the cooler air will be more effective in condensing the refrigerant being compressed.

A further object is the provision of a system of the type above described using two condensers arranged in parallel with a pump separate from the compressor for circulating refrigerant through the system with the compressor out of operation when the temperature of the air surrounding the condenser which is positioned in the location subject to wide temperature variations becomes lower than the temperature which it is desired to maintain in the air surrounding the evaporator.

Other objects will become apparent upon a study of the specification, claims, and appended drawings wherein like reference characters represent like parts in the various views and where-

in:

Figure 1 is a schematic view of one form of refrigeration system embodying my invention;

Figure 2 is a view similar to Figure 1 but illustrating a different control means for the refrigerating apparatus; and

Figure 3 is a modification of the system of Figure 1 wherein two condensers are provided, these condensers being arranged in parallel.

Referring more specifically to Figure 1, a compressor is represented by the reference character 10, this compressor being driven by any suitable means as by a motor 11, this motor being controlled in a manner to be hereinafter described. Connected to the high pressure side

5 of the compressor 10 is a pipe 12 leading to a condenser 13, the outlet of the condenser being connected to a receiver 14. A pipe 15 is connected to the outlet of the receiver 14 and leads to the inlet of a pump 16, this pump being connected to a driving motor 11. The outlet of the pump 16 is connected by means of a pipe 19 to an expansion valve 20 which controls the flow of refrigerant into the evaporator coil 21. The evaporated refrigerant flows from the evaporator coil 21 through a pipe 22 back to the inlet of the compressor 10. The evaporator coil 21 is shown as being mounted in a suitable fixture 24 and located within the fixture is a thermostat 25. This thermostat is shown to comprise a bellows 26 which is filled with a suitable volatile fluid, this bellows controlling the position of a lever 27 which is pivoted at 28 and biased by means of a spring 29 into engagement with the top of the bellows. Carried by the lever 27 is a mercury switch 30, this switch including contacts 31 and 32 and a mercury element 33. When the temperature within the fixture 24 is at a high enough value, the bellows 26 is expanded as illustrated and switch 30 is accordingly tilted to the position wherein the contacts 31 and 32 are electrically connected by the mercury element 33. Upon a drop in temperature in the box, the bellows 26 contracts and after the temperature drops to a predetermined value the switch 30 will be tilted to a position wherein the circuit through the contacts 31 and 32 is interrupted.

35 Connected to the pipe 12 through which the high pressure refrigerant flows is a bellows 35. This bellows controls the position of a lever 36 pivoted at 37 and biased by means of a spring 38 into engagement with the upper portion of the bellows, the lever 36 carrying a mercury switch 39. When the pressure of the refrigerant leaving the compressor is below an excessively high value the switch 39 will be tilted to the position illustrated wherein contacts 40 and 41 are electrically connected to the mercury element therein. However, when the pressure becomes excessive the mercury switch will be tilted in the opposite direction whereupon the circuit through the contacts 40 and 41 will be interrupted.

50 The condenser 13 will preferably be positioned in a location which is subject to wide temperature variations such as outside the building for example. Positioned adjacent the condenser is a thermostat 45 which is subject to the temperature of the air surrounding the condenser 13.

The thermostat 45 may include a bellows 46 provided with a suitable volatile fill, this bellows controlling the position of a lever 47 pivoted at 48 and biased by means of a spring 49 into engagement with the upper portion of the bellows 46. Carried by the lever 47 is a mercury switch 52, this switch including contacts 53, 54, 55, and 56. When the temperature adjacent the condenser 13 is above a predetermined value, the bellows 46 is expanded and the switch 52 is tilted in the direction shown so that contacts 55 and 56 are connected by means of the mercury element in the switch 52. However, when the temperature adjacent the condenser falls to a predetermined low value, the contraction of the bellows 46 will cause the mercury switch 52 to be tilted in the other direction wherein the contacts 53 and 54 are connected together by the mercury element.

For supplying power to the motors 11 and 17 line wires 60 and 61 are provided, these line wires being connected to a suitable source of power (not shown). When the temperature within the fixture 24 is above a predetermined value and switch 30 is in the position shown and when the temperature adjacent the condenser 13 is high enough so that switch 52 is tilted to the position shown, the motor 11 which drives the compressor 10 will be energized by means of the following circuit: from line 60 through conductors 62, mercury switch 30, conductor 63, terminals 55 and 56 of mercury switch 52, conductor 64, the mercury switch 39, it being assumed that the pressure on the discharge side of the compressor is not excessive at this time, conductor 65 through motor 11 and conductor 66 to the line wire 61. No current flows through the motor 17 at this time so that the cooling of the fixture 25 by the evaporator 21 is effected by the compressor 10 in the conventional manner. The pump 16 is shown as being a centrifugal pump so that the flow of refrigerant therethrough is not impeded by reason of the fact that this pump is not operating at this time. In the event however, that a pump of the positive displacement type were used in place of the centrifugal pump 16, a valve controlled by-pass could be provided around the pump to permit the flow of refrigerant through the system when the pump is not in operation. The compressor 10 will continue to operate as long as the switches 30, 39, and 52 remain tilted in the directions illustrated. Should the temperature of the fixture get sufficiently low so that switch 30 is tilted in the opposite direction the motor 10 will shut down. Likewise should the discharge pressure of the refrigerant leaving the compressor become excessively high, the switch 39 will be tilted by the bellows 35 in a position to interrupt operation of the compressor motor.

Should now the temperature of the air surrounding the condenser 13 become sufficiently low, or in other words, lower than the temperature which it is desired to maintain in the fixture 25, the bellows 46 will contract sufficiently to tilt switch 52 in a position wherein the contacts 53 and 54 are connected together by the mercury element. This tilting of the switch 52 in this direction interrupts the circuit through the compressor motor, thus placing the compressor out of operation. If the temperature of the fixture is still above the desired value a circuit will be established through the motor 17 as follows: from the line wire 60 through conductor 62, the mercury switch 30, conductor 63, 75

contacts 54 and 53 of mercury switch 52, conductor 68 through the motor 17, and conductor 69 to the line wire 61. The motor 17 is now placed in operation and causes pump 16 to pump refrigerant from the condenser 13 through the evaporator coil 21 and back to the condenser 13. A suitable by-pass 70 controlled by a check valve 71 is provided for permitting the refrigerant to by-pass the compressor 10 when the compressor is not operating. This valve will permit flow of refrigerant through the valve 71 in the direction of the arrow but will not permit flow in the reverse direction so that when the compressor 10 is in operation the pressure on the left side of the valve will be considerably higher than on the opposite side so that no refrigerant flows through the by-pass 70. However, when the compressor 10 is shut down and pump 16 is in operation the pressure on the left side of the valve will be lower than on the right side so that refrigerant will by-pass the compressor 10. This by-pass and check valve 71 might be omitted if the valves of the compressor are not excessively stiff so that refrigerant can flow through the compressor in response to operation of the pump 16. A fan 72 is driven by the motor 17 and causes a circulation of air over the condenser 13 when the motor 17 is operating to facilitate the cooling thereof.

30 It should now be apparent that when the pump 16 is operating due to the reason that the temperature of the fixture is above the desired value and that the temperature of the air surrounding the condenser is below the value which it is desired to maintain in the fixture 24, then the system is operating as a simple heat transfer system, the heat of the fixture being transferred to the cold air surrounding the condenser 13. This provides for great economy of operation since the pump 16 can be operated with a considerably less expenditure of energy than the compressor 10 while at the same time effecting the necessary cooling of the fixture 24 when the temperature of the air surrounding the condenser is at a low enough value. It will therefore be seen that with this system, the temperature of the fixture is cooled very economically when the temperature of the air surrounding the condenser is sufficiently low.

55 Referring now to Figure 2 the refrigeration system except for the control means is illustrated as being identical with that of Figure 1. Instead of the thermostat 25 responsive to the temperature of the air within the fixture 24, a device responsive to the suction pressure of the compressor is provided, this device giving an indication of the temperature of the evaporator. This device may comprise a bellows 75 connected by means of a pipe 76 to the pipe 22 connecting the evaporator to the inlet of the compressor 10. The bellows 75 controls the position of a mercury switch 78 mounted on a lever 79 pivoted at 80, this lever being biased by means of a spring 81 into engagement with the upper portion of the bellows 75. When the pressure on the low side of the system falls to a predetermined value the bellows 75 will contract and move the mercury switch to a position wherein the circuit through the contacts 83 and 84 is interrupted by the mercury element.

70 When the suction pressure is high enough so that the switch 78 is tilted in the position illustrated the evaporator coil temperature will be above the desired value, it being understood that the suction pressure is an indication of evaporator

temperature and the compressor motor 11 will be placed in operation, assuming that the temperature of the air surrounding the condenser 13 is not too low and that the pressure on the discharge side of the compressor is not too high, by means of the following circuit: from the line 60 through conductor 86, mercury switch 78, conductor 89, the mercury switch 39, conductor 90, contacts 55 and 56 of the mercury switch 52, conductor 91, compressor motor 11, and conductor 92 to the line 61. The compressor will continue to operate until either the suction pressure in the system drops to a predetermined low value indicating that the coil temperature has dropped to a low enough value, until the pressure on the high pressure side of the system exceeds a certain value, or until the temperature of the air surrounding the condenser 13 drops to a sufficiently low value. Assume now that the temperature of the air surrounding the condenser is at such a low value that switch 52 is tilted to the position wherein the contacts 53 and 54 are connected together by the mercury element, that the switches 39 and 78 are in the positions illustrated, the motor 17 will be energized through the following circuit: from the line wire 60 through conductor 86, switch 78, conductor 89, switch 39, conductor 90, contacts 54 and 53 of the mercury switch 52, conductor 94, the motor 17 and conductor 95 to the line wire 61. The compressor 10 at this time is not operating since the circuit through the contacts 55 and 56 of the switch 52 has been interrupted and the pump 16 will circulate refrigerant through the system in the same manner as in Figure 1. It will now be apparent that the systems of Figure 1 and Figure 2 operate in a similar manner except that in Figure 1 the operation of the compressor 10 and the pump 16 is controlled by the temperature of the fixture 24 whereas in Figure 2 they are controlled in accordance with the suction pressure of the system or in other words, according to the temperature of the evaporator coil.

Referring now to Figure 3, a refrigeration system similar to that of Figure 1 is illustrated except that the means for condensing the refrigerant comprises a pair of condensers 100 and 101 arranged in parallel, both of these condensers having their inlets connected to the discharge side of the compressor 10 and their outlets connected to the receiver 14. The compressor 100 may be located outside the building as illustrated where it is subjected to variations in outdoor temperature whereas the condenser 101 may be located inside the building adjacent the compressor 10 which in turn may be remotely located from the cooling chamber 24 as for example, in the basement of a building. The temperature of the air surrounding the condenser 101 will fluctuate relatively little throughout the year whereas the temperature of the air surrounding the evaporator 100 may fluctuate between relatively high and low values depending upon the season of the year. During those portions of the year where the outdoor temperature is relatively high, the condenser 100 will have relatively little or no condensing effect on the refrigerant and most of the condensing will take place within the condenser 101. These condensers should each have sufficient capacity so that either one of the condensers may do all the condensing of the refrigerant that is necessary for satisfactory operation of the system.

During cool weather the outdoor temperature will drop below the temperature of the air sur-

rounding the condenser 101 so that a considerable portion of the condensing of the refrigerant may take place in the condenser 100. When the temperature outdoors falls below the temperature which it is desired to maintain in the fixture 24, the thermostat 45 which responds to outdoor temperature will transfer the control of the system from the compressor 10 to the pump 16 in the same manner as has been set forth in connection with Figure 1, and the system will then operate as an ordinary heat transfer system for transferring the heat from the fixture 24 to the outdoor air by means of the condenser 100 without the necessity of operating the compressor 10.

Accordingly with this system, variations in relative indoor and outdoor temperatures are most effectively utilized for efficiently operating the refrigerating system so that when the outdoor temperature is lower than the indoor temperature the condensing will take place in the condenser exposed to the outdoor air and conversely when the outdoor temperature becomes relatively high most or all of the condensing of the refrigerant will take place in the condenser 101. It will be unlikely in a system of the type shown in this figure that the air surrounding the condenser 101 will ever become lower than the temperature which it is desired to maintain in the fixture 24 so that the pump 16 responds only to the outdoor temperature. However, if for some reason or other the temperature surrounding the condenser 101 should at certain times be lower than the temperature of the air surrounding the condenser 100 and should also be lower than the temperature it is desired to maintain in the fixture 24, the pump 16 may be operated both in response to the indoor and outdoor temperature so that when either of these temperatures is lower than the temperature that it is desired to maintain in the fixture 24 the pump will be operated and the compressor placed out of operation. The controller 25 responsive to the temperature of the fixture 24 may if desired be replaced by a suction pressure controller as in Figure 2.

Having described the preferred forms of my invention, many modifications may become apparent to those skilled in the art. For example, any other suitable system for controlling the operation of the compressor may be substituted for those illustrated. If desired, pump 16 might be operated whenever the compressor operates as well as at other times, thus assisting in the circulation of the refrigerant. In such case, when the compressor and pump are in operation simultaneously, or if the fan 72 be run continuously, the condenser associated therewith may be operated as an evaporative condenser. The systems illustrated may be used with multiple coil installations as well as with single coil installations as illustrated. It should therefore be understood that my invention is to be limited only by the scope of the appended claims.

I claim as my invention:

1. A refrigeration system including a compressor, a condenser and an evaporator, said condenser being positioned in a location subject to temperature variations, means for causing a circulation of refrigerant from the condenser to the evaporator and back to the condenser, and means responsive to the temperature of the air surrounding said condenser for interrupting operation of the compressor when the temperature drops to a low predetermined value and caus-

ing operation of said refrigerant circulating means.

2. A refrigerating system including a compressor, a condenser and an evaporator, said compressor being arranged to circulate refrigerant through said condenser and said evaporator, said condenser being positioned in a location subject to temperature variations, means for controlling the operation of the compressor including means responsive to the temperature of the air surrounding said condenser, and means independent of the operation of the compressor for causing circulation of refrigerant from the condenser to the evaporator and back to the condenser.

3. A refrigeration system including a compressor, a condenser and an evaporator, said condenser being positioned in a location subject to temperature variations, means independent of the operation of the compressor for causing circulation of refrigerant from the condenser to the evaporator and back to the condenser, controlling means for the compressor and said circulation causing means, said controlling means including means responsive to the temperature of the air surrounding said condenser for causing operation of the compressor when said temperature is above a predetermined value and for interrupting operation of the compressor and causing operation of the circulation causing means when said temperature is below a predetermined value.

4. A refrigeration system including a compressor, a condenser, and an evaporator, said condenser being positioned in a location subject to temperature variations, means independent of the operation of the compressor for circulating refrigerant from the condenser to the evaporator and back to the condenser, means responsive to a condition which is a measure of the demand for cooling for controlling the operation of the compressor or the circulating means, and means responsive to the temperature of the air surrounding said condenser for placing the compressor or the circulating means under the control of said last named means.

5. A refrigeration system including a compressor, a condenser and an evaporator, said condenser being positioned in a location subject to temperature variations, a pump separate from the compressor for circulating refrigerant from the condenser to the evaporator and back to the condenser, means responsive to a condition which is a measure of the demand for cooling by the evaporator for selectively controlling the operation of the compressor or the pump, and means responsive to the temperature of the air surrounding the condenser for placing the compressor under the control of said condition responsive means when the temperature is above a predetermined value and for placing the pump under the control of said condition responsive means when the temperature is below a predetermined value.

6. A refrigeration system including a compressor, a condenser and an evaporator, said condenser being positioned in a location subject to temperature variations, a pump separate from the compressor for circulating refrigerant from the condenser to the evaporator and back to the condenser, means responsive to a condition which is a measure of the demand for cooling by the evaporator for selectively controlling the operation of the compressor or the pump, means responsive to the temperature of the air surround-

ing the condenser for placing the compressor under the control of said condition responsive means when the temperature is above a predetermined value and for placing the pump under the control of said condition responsive means when the temperature is below a predetermined value, and means operated conjointly with said pump for causing a circulation of air past said condenser.

7. A refrigeration system including a compressor, a condenser and an evaporator, said condenser being positioned in a location subject to temperature variations, a pump for causing a circulation of refrigerant from the condenser to

10 15 the evaporator and back to the condenser when the compressor is not operating, means responsive to the temperature of the air being cooled by the evaporator selectively in control of the compressor and the pump, and means responsive

20 to the temperature of the air surrounding the condenser for placing the compressor under the control of the first named temperature responsive means when the temperature of the air surrounding the condenser is above a predetermined

25 value and for placing the pump under the control of the first named temperature responsive means when the temperature of the air surrounding the condenser is below a predetermined value.

8. A refrigeration system including a compressor, a condenser and an evaporator, said condenser being positioned in a location subject to temperature variations, a pump for causing a circulation of refrigerant from the condenser to

35 the evaporator and back to the condenser when the compressor is not operating, means responsive to the temperature of the air being cooled by the evaporator selectively in control of the compressor and the pump, means responsive to the temperature of the air surrounding the condenser for placing the compressor under the control of the first named temperature responsive means when the temperature of the air surrounding the condenser is above a predetermined

40 45 value and for placing the pump under the control of the first named temperature responsive means when the temperature of the air surrounding the condenser is below a predetermined value, and means operated conjointly with the pump for causing a circulation of air over said condenser.

9. A refrigeration system including a compressor, a condenser and an evaporator, said condenser being positioned in a location subject to temperature variations, a pump for causing a circulation of refrigerant from the condenser to the evaporator and back to the condenser when the compressor is not operating, means responsive to the pressure on the suction side of the refrigeration system for selectively controlling the operation of the compressor and the pump, and means responsive to the temperature of the air surrounding the condenser for placing the compressor under the control of the pressure responsive

60 65 means when the temperature of the air surrounding the condenser is above a predetermined value and for placing the pump under the control of the pressure responsive means when the temperature of the air surrounding the condenser is below a predetermined value.

10. A refrigeration system including a compressor, a condenser and an evaporator, said condenser being positioned in a location subject to temperature variations, a pump for causing a circulation of refrigerant from the condenser to

the evaporator and back to the condenser when the compressor is not operating, means responsive to the pressure on the suction side of the refrigeration system for selectively controlling the operation of the compressor and the pump, means responsive to the temperature of the air surrounding the condenser for placing the compressor under the control of the pressure responsive means when the temperature of the air surrounding the condenser is above a predetermined value and for placing the pump under the control of the pressure responsive means when the temperature of the air surrounding the condenser is below a predetermined value, and means operated conjointly with said pump for causing a circulation of air over said condenser.

11. A refrigeration system including a compressor, an evaporator, and a pair of parallelly arranged condensers, one of said condensers being located adjacent said compressor and the other of said condensers being positioned in a location subject to wide temperature variations, means independent of the operation of the compressor for circulating refrigerant from the condensers to the evaporator and back to the condensers, means responsive to a condition which is a measure of the demand for cooling by the evaporator for controlling the operation of the compressor or the circulating means, and means responsive to the temperature of the air surrounding said last named condenser for selectively placing the compressor or the circulating means under the control of said last named means.

12. A refrigeration system including a compressor, an evaporator, and a pair of parallelly arranged condensers, one of said condensers being located adjacent said compressor and the other of said condensers being positioned in a location subject to wide temperature variations, means independent of the operation of the compressor for circulating refrigerant from the condensers to the evaporator and back to the condensers, means responsive to a condition which is a measure of the demand for cooling by the evaporator for controlling the operation of the compressor or the circulating means, means responsive to the temperature of the air surrounding said last named condenser for selectively placing the compressor or the circulating means under the control of said last named means, and means operated conjointly with said circulating means for causing a circulation of air over said last named condenser.

13. A refrigeration system including a compressor, an evaporator, and a pair of parallelly arranged condensers, one of said condensers being located adjacent said compressor and the other of said condensers being positioned in a location subject to wide temperature variations, a pump for causing a circulation of refrigerant from the condensers to the evaporator and back to the condensers, means responsive to the temperature of the air being cooled by the evaporator for controlling the operation of the compressor and the pump, and means responsive to the temperature of the air surrounding said last named condenser for placing the compressor under the control of the first named temperature responsive means when the temperature of the air surrounding said condenser is above a predetermined value and for placing the pump under the control of the first named temperature responsive means when the temperature of the air sur-

rounding said condenser is below a predetermined value.

14. A refrigeration system including a compressor, an evaporator, and a pair of parallelly arranged condensers, one of said condensers being located adjacent said compressor and the other of said condensers being positioned in a location subject to wide temperature variations, a pump for causing a circulation of refrigerant from the condensers to the evaporator and back to the condensers, means responsive to the temperature of the air being cooled by the evaporator for controlling the operation of the compressor and the pump, means responsive to the temperature of the air surrounding said last named condenser for placing the compressor under the control of the first named temperature responsive means when the temperature of the air surrounding said condenser is above a predetermined value and for placing the pump under the control of the first named temperature responsive means when the temperature of the air surrounding said condenser is below a predetermined value, and means operated conjointly with the pump for causing a circulation of air over said last named condenser.

15. In a refrigeration system, an evaporator, a condenser positioned in a location subject to variations in temperature, a first means for causing a circulation of refrigerant through the condenser and evaporator and causing operation of the evaporator to effect cooling even though the temperature at the location of the condenser is not relatively low, a second means for causing a circulation of refrigerant through the condenser and evaporator and causing operation of the evaporator to effect cooling only when the temperature at the location of the condenser is relatively low, and means responsive to the temperature at the location of the condenser for controlling the operation of the first circulating means.

16. In a refrigeration system, an evaporator, a condenser positioned in a location subject to variations in temperature, a first means for causing a circulation of refrigerant through the condenser and evaporator and causing operation of the evaporator to effect cooling even though the temperature at the location of the condenser is not relatively low, a second means for causing a circulation of refrigerant through the condenser and evaporator and causing operation of the evaporator to effect cooling only when the temperature at the location of the condenser is relatively low, and means for controlling operation of the first and second circulating means, said means including means responsive to a condition which is a measure of the demand for cooling by the evaporator and means responsive to the temperature at the location of the condenser.

17. A refrigeration system including a compressor, an evaporator and condensing means, said condensing means being cooled by a medium subject to temperature variations and which at times falls below the necessary operating temperature of the evaporator, whereby at times compression of the refrigerant is necessary for condensing while at other times the refrigerant may be condensed without compression, and means actuated when compression of the refrigerant is unnecessary for condensing the same for placing said compressor out of operation, and means for circulating refrigerant when the compressor is not operating.

18. A refrigeration system including evaporating means, condensing means, and circulating

means for circulating refrigerant from the condensing means to the evaporating means, said condensing means being cooled by a medium subject to temperature variations and which at times falls below the necessary operating temperature of the evaporating means, whereby at times compression of the evaporated refrigerant is necessary for condensing the same and at other times the refrigerant may condense without compression, said circulating means being arranged to selectively circulate the refrigerant without substantial compression or to compress said refrigerant, and means actuated when compression of the refrigerant is unnecessary for condensing the same for controlling said circulating means in a manner to prevent substantial compression of the refrigerant thereby.

19. A refrigeration system including evaporating means, condensing means, means including a compressor for withdrawing evaporated refrigerant from the evaporating means, compressing it, and discharging the compressed refrigerant into the condensing means, means including a circulating pump for withdrawing liquid refrigerant from the condensing means and delivering it to the evaporating means, said condensing means being cooled by a medium subject to temperature variations and which at times falls below the necessary operating temperature of the evaporating means, whereby at times compression of the refrigerant is necessary for condensing the same and at other times the refrigerant may condense without compression, and means actuated when compression of the refrigerant is necessary for condensing the same for operating the compressor, said last named means placing the compressor out of operation and operating said circulating pump when compression of the refrigerant is unnecessary for condensing the same.
